UNITED STATES PATENT OFFICE.

HENRY HARRISON PACKER, OF BOSTON, MASSACHUSETTS.

PUNCHING-MACHINE.

SPECIFICATION forming part of Letters Patent No. 272,151, dated February 13, 1883.

Application filed August 16, 1882. (No model.)

To all whom it may concern:

Be it known that I, HENRY HARRISON PACKER, a citizen of the United States, residing at Boston, in the county of Suffolk and State of Massachusetts, have invented certain new and useful Improvements in Punching-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to punching-machines, to be operated either by a hand or foot pedal or power, as may be desired; and it consists of three principal features: first, in having a movable head independent of the "yoke," so called, as heretofore generally used on punching-machines, this movable head carrying the punch-holder and punch, the latter, by means of said holder and the movable head, being operated by mechanism hereinafter more fully described.

The second feature of my improvements consists in the means for adjusting the length of the punch, according as it wears away or becomes shortened through sharpening or the work to be done, and is accomplished by passing the upper portion of the punch-holder through the top of the movable head, and having attached thereto, both above and below said upper end, two hand-nuts, the top one to raise or lower the punch-holder and punch, and the lower or under one to clamp said holder securely in place when its desired position is attained.

The third feature of my improvements consists in a movable joint in the middle, or approximately thereto, of the punch-holder.

By my improvements the ordinary yoke of the punching-machine, which usually takes the entire strain, simply acts as a guide to keep the punch-holder in vertical paths of movement, as there is no strain whatsoever brought to bear upon it when the machine is at work, except to steady and prevent any shearing movement of the punch in its active stroke;

but the strain proper is imparted through the punch-holder to the top of the movable head, which, if the latter had a tendency to spring, which generally occurs under severe strains in other machines, would throw the punch out of proper vertical adjustment. The socketed joint in the middle of the punch-holder is provided to obviate and completely nullify said spring and allow of great strain and even springing of the movable head without in the least affecting the movement of the punch-holder and punch connected thereto.

The drawings accompanying this specification represent in Figure 1 a side elevation of a punching-machine embodying my improvements, and Fig. 2 a vertical section through the punch-holder and punch. Fig. 3 is a horizontal cross-section through the punch-holder, movable head, and yoke, showing guides for the punch-holder.

In these drawings, A represents a frame or stand, to which the operative mechanism is attached and supported; B, the base or standard for the yoke D, formed in one casting and bolted to the frame A; a a, b b, c c, and d d, side and end braces for strengthening said frame. The yoke D is of the shape usual in such yokes, but instead of being entirely solid has a solid head or portion, e, and two extended ribs or flanges, f f, between which the movable head E reciprocates. The front portion, e, of the yoke D is, moreover, cast to fit the punch-holder F, and, further, provided with guide-plates g g, secured with suitable bolts to enable perfect vertical adjustment of the punch to be made. This punch-holder F may be of any suitable size or dimensions in cross-section to give it proper strength.

The punch-holder F, as previously mentioned, is composed of two portions—*h* the lower and *i* the upper. The bottom portion, *h*, is adapted to slide in guides *g g*, and its lower extremity is fitted to receive and retain the punch *j*, while its top is provided with a hole, *k*, spherical at the bottom, as shown in Fig. 1 of the drawings, to receive the projecting ball-joint *l*, to be hereinafter described, of the upper portion, *i*. This upper portion of said holder F is peripherally screw-threaded its entire

length to receive two hand-adjusting nuts, H I. The screw-threaded portion *i* passes freely through the extremity *G* of the head *E*, and consequently the weight of the punch-holder 15 falls upon the hand-nut *I*, while *H* acts as a clamp-nut. Furthermore, as the latter takes the entire strain on the active stroke, I have shown it of considerable length in order to give the requisite strength on the thread to prevent the latter being stripped, and for the same purpose generally have the extremity of said nut *H* to bear firmly against the shoulder *m* in the portion *G* when in proper adjustment.

15 To secure the two parts *i j*, composing the punch-holder, together, I bore a hole through the ball-joint *l* and likewise the upper part of *h*, as shown, and insert therein a pin or bolt, *n*. I also slightly cut up the edges of the shoulder at *o*, Fig. 2, and this, in connection with the spherical socket, gives the requisite motion sufficient to obviate any spring or yielding of the head *E* under severe thrusts and strains 20 and allows the punch to play in vertical paths of movement by means of the yoke *D* and guides *g g*, upon which no strain falls except to resist any shearing tendency the punch may have as it passes through the metal to be operated on. The movable head *E* is in shape a 25 half-inverted **U**, looking at it from one side, and in cross-section "double" **T**, so-called, in order to give it great strength. This head is held in its proper position at the top by means of its connection with the punch-holder *F* and 30 its guides *g g*. The lower portion is attached by the bolt *p* and link or links *M* to one corner of a casting, *N*, by the bolt *P*, this lever being secured by a hanger, *r*, to the under side of the base *B* by the bolt *s*, and rocking thereon when 35 occasion requires; or the link *M* can be dispensed with and the movable head *E* made to extend to the lever *N*.

To the lower corner of the rocking lever *N* is secured, by means of the bolt *t*, one end of a 40 knuckle or toggle joint, *S*, the upper part of which is pivoted to the bed *B* at *s'*. This portion *T* of the knuckle-joint *S* is a long triangular-shaped bar, rectangular in cross-section, and has connected to its extreme outer end a 45 rod, *U*, which extends downward and is attached near the pivoted end of a foot-lever. Furthermore, this foot-lever *X* is fastened to one of the braces *b*, and is kept in proper position—that is, ready for an active stroke—by 50 the rod *u'* and counterpoise-weight *V*. Said rod *u'* is pivoted to the lever *X* and likewise to the rod *u*, which latter is suspended from a rocker-shaft, *v*, supported on the hangers *x x*. This counterpoise-weight *V* is of sufficient 55 weight and so arranged as to overcome the friction and gravity of the entire working parts of the machine, and to return said mechanism after an active stroke to its inactive or passive condition, ready for a second stroke.

60 Having thus described the mechanical details of construction of my improvements, I

will now proceed to show the movements of the parts relatively to each other, the machine being in an inactive position, but ready for an active stroke, as shown in Fig. 1 of the 70 drawings. The operator placing his foot on the end of the lever *X* depresses it, and likewise at the same time, by means of the rod *U*, connected therewith, the outer extremity or nose of the upper part of the knuckle-joint *S*, 75 and thereby straightens said joint, by which means the lowest corner of the bell-lever *N* is thrust back, swinging on the pivot *s* as its center. This thrusting back of the bell-lever by the intermediary connecting-link *M* depresses and draws down the movable head *E*, and with it the punch-holder *F* and punch *j*, driving said punch through the metal placed below it.

I do not restrict myself to the precise manner, as herein shown, of obtaining the power, as said power can be obtained in divers ways, and increased or diminished by the alterations of the position of the pivots.

This machine can be used for "drawing up," so called, equally as well as for punching, and can be used on very light metal without crushing, owing to its perfect freedom from lateral shearing or deviation from the vertical line of movement common in presses of the 90 ordinary construction, unless a very heavy press is used compared with the work to be accomplished.

In ordinary presses the resistance to the punching pressure is borne by the yoke *D*, 100 and in case this breaks an entire new machine must be substituted and considerable expense incurred; but with a movable head, as previously stated, the yoke *D* is relieved from the entire strain of the work accomplished, 105 and the casting *E*, in case it is broken, can readily be replaced by removing the adjusting-screw *I* and pin or bolt *p* and inserting a new one.

This machine can be readily operated by 110 power by attaching the power to the movable head *E* direct or to the knuckle-joint *S*, as most convenient or desirable.

I claim—

1. A movable head and punch-holder attached thereto, in combination with a yoke which guides said head and holder, and a counterbalance-weight, bell-crank lever *N*, and connecting and actuating mechanism, substantially as set forth.

2. In combination with a treadle, counterbalance-weight, knuckle-joint, and bell-crank lever *N*, a head and punch-holder reciprocated by the foregoing devices, and a yoke or frame in which said head and punch-holder are 125 guided.

3. A punch-holder consisting of two parts connected by a socketed joint and having the upper part screw-threaded, in combination with a yoke in which the lower part of said 130 holder is guided, the head through which the upper part of said holder passes, and the

nuts H and I, applied to the threaded part of said holder above and below said head, as set forth.

4. A punch-holder consisting of two parts connected by a socketed joint, in combination with a head to which the upper part of said holder is attached, and a yoke in which the lower part of said holder is guided, substantially as set forth.

In testimony whereof I affix my signature in presence of two witnesses.

HENRY HARRISON PACKER.
